UNITED STATES PATENT OFFICE.

EDWARD T. YOUNG, OF BOSTON, MASSACHUSETTS.

METHOD OF SUPPLYING ENERGY TO ENGINES.

No. 902,310.

Specification of Letters Patent.

Patented Oct. 18, 1908.

Application filed June 2, 1906. Serial No. 319,961.

To all whom it may concern:

Be it known that I, EDWARD T. YOUNG, of Boston, in the county of Suffolk and State of Massachusetts, a citizen of the United States, have invented a new and useful Improvement in the Methods of Supplying Energy to an Engine, of which the following is a specification.

My invention consists mainly in an improved method of igniting and burning fuel in which external heat is primarily relied upon for the purpose of igniting the fuel. The fuel is preferably some form of hydrocarbon. Heretofore the methods most commonly adopted for the ignition and combustion of such fuel have been:

1. By compression of an explosive mixture of gas and air, as in the Otto type, and igniting the same by an electric spark or hot tube ignition.

2. By atomizing or mixing with air and injecting the mixture and burning the same as it goes into the combustion chamber of the cylinder.

3. By vaporizing fuel by heat and thereafter supplying to it sufficient air to make it an explosive mixture.

4. By compressing atmospheric air in a cylinder to a point—about 500 lbs.—sufficient to raise it to a temperature high enough to ignite the fuel and injecting the fuel so that it burns as it goes into the cylinder.

In 1 and 3 the mixture is an explosive mixture with its attendant instantaneous generation of high pressures and temperatures and strain upon the metal.

2 is a method entirely distinct from my method and presents many difficulties in practice.

In 4 the high compression pressure previous to the combustion of the fuel and the additional pressure and temperature of combustion built upon that, gives a degree of temperature and pressure that is as difficult to handle as the explosive method.

All these methods have the disadvantage that they generate high pressures and temperatures and require that the engines be built so as to stand the high and sudden rise in temperatures and pressures resulting from these methods of combustion. I have devised a method of ignition which differs from these in that the fuel is fed into air confined at any desired pressure heated by means dependent to no extent upon the pres-

sure of the air within the chamber, and there is ignited, not because of the air pressure, but because of the temperature of the air heated by external means, preferably by the walls 60 of the chamber. By external means I mean any means external to the medium into which the fuel is injected, such for example,—as the heat developed by the combustion of the previous charge and stored in the 65 walls of the chamber but not the heat resulting from the compression of the specific quantity of non-combustible medium into which a particular fuel charge is injected. Under these conditions air at a comparatively 70 low compression may be used and a low combustion pressure can be developed, and such low pressure may be prolonged and sustained so as to give the same average pressure as would follow from an initial 75 high pressure without the corresponding disadvantages. Under this method of ignition resultant pressures shown by the indicator card are similar to those used in the steam engine, the admission of steam corresponding with the admission of fuel under 80 this method.

I have shown in the drawings sections of apparatus by which my method may be carried out.

Figure 1 is a cross section of a cylinder and fuel-injecting means, and Fig. 2 is a longitudinal section taken on line 2—2 of Fig. 1.

A is a cylinder and B is a piston which may both be of any ordinary style. C is the combustion chamber which is fed with fuel from a jacketed jet D, E and E' showing the pipes for water circulation through the jacket. F is the oil supply, the passage of the oil into the combustion chamber C being controlled 90 by the needle G which is operated in any convenient way. These parts as shown are more fully described in an application for a patent, Serial No. 319,962, filed contemporaneously with this application.

H is a burner by means of which external heat may be applied more especially when starting up the engine.

J shows the connection with the valve chest.

My method is of such a character that it may be carried out in a variety of well known forms of engine and it therefore is unnecessary to describe fully an apparatus for utilizing it.

To restate the novel features of my invention, I would say that to carry it out I con-

85

fine a body of air under more or less compression, but at a pressure insufficient of itself to ignite the fuel. Into this the fuel is injected and it ignites because the temperature of the air has been raised by external heat to the igniting point and the amount of pressure generated will depend upon the time in which the charge of fuel is injected and the quantity of fuel injected.

10. What I claim as my invention is:—

1. An improved method of supplying energy to an engine which consists in confining a body of non-combustible combustion-sustaining gas, preferably atmospheric air, in a chamber under a pressure insufficient to ignite the fuel to be used, heating to a fuel-igniting temperature a sufficient amount of said combustion-sustaining gas to ignite a fuel charge by external means, and injecting fuel into it, whereby said fuel will be ignited, as described.
2. An improved method of supplying energy to an engine which consists in compressing a body of non-combustible combustion-sustaining gas, preferably atmospheric air, in a chamber to a degree insufficient to ignite the fuel to be used, and heating by external means a sufficient amount of said combustion-sustaining gas to a temperature sufficient to accomplish the ignition of the fuel injected into it, and injecting such fuel into it whereby said fuel will be ignited and burned, as described.
3. An improved method of supplying energy to an engine which consists in compressing a body of non-combustible combustion-sustaining gas, preferably atmospheric air, in a chamber, to a degree insufficient to ignite the fuel to be used, and heating by external means to an igniting temperature a sufficient amount of said combustion-sustaining gas to accomplish the ignition of the fuel in-

jected into it, and injecting such fuel into it whereby said fuel will be ignited and burned, as described.

4. An improved method of supplying energy in the form of pressure to an engine, which consists in heating a body of combustion-sustaining gas, preferably atmospheric air, in a chamber connected to an engine, said gas being under pressure, the temperature of compression being insufficient to ignite the fuel, said chamber being heated sufficiently to impart to air therein contained heat to a degree sufficient to ignite fuel, and then injecting fuel into said heated air, as described.

5. An improved method of supplying energy in the form of pressure to an engine, which consists in heating a body of combustion-sustaining gas, preferably atmospheric air, in a chamber connected to an internal combustion engine, said gas being under pressure, the temperature of compression being insufficient to ignite the fuel, said chamber being heated sufficiently to impart to air therein contained, heat to a degree sufficient to ignite fuel, and then injecting fuel into heated air, as described.

6. An improved method of supplying energy in the form of pressure, which consists in heating a body of combustion-sustaining gas, preferably atmospheric air, in a chamber connected with the cylinder of an internal combustion engine, said gas being under pressure, the temperature of compression being insufficient to ignite the fuel, said chamber being heated sufficiently to impart to air therein contained, heat to a degree sufficient to ignite fuel, and then injecting fuel into said heated air, as described.

EDWARD T. YOUNG.
